CHARLES J. SIBBALD, CHARLES T. A. SIBBALD, AND JOHN O. SIBBALD, OF TROY,
NEW YORK.

LOOP-TRANSFERRING DEVICE.

1,353,793.

Specification of Letters Patent. Patented Sept. 21, 1920.

Application filed June 18, 1919. Serial No. 305,052.

To all whom it may concern:

Be it known that we, CHARLES J. SIBBALD, CHARLES T. A. SIBBALD, and JOHN O. SIBBALD, citizens of the United States, residing 5 at 769 Third avenue, Troy, in the county of Rensselaer and State of New York, have invented certain new and useful Improvements in Loop-Transferring Devices, of which the following is a specification.

10 This invention relates to a method of and means for transferring the stitches from a knitting machine and assembling such stitches for uniting by a looper or sewing machine.

15 The invention is particularly applicable to closing the toe-pocket formed on the foot portion of a stocking, and the means employed are engaged with the loops or stitches of the final course of the article and removed bodily from the knitting machine.

20 The means is adapted to arrange the loops or stitches of one-half of such final course in predetermined relation with the stitches of the other half of such course, so that opposed stitches or loops are alined. The alined loops or stitches are then picked up on holding pins or points, each pin engaging a pair of loops, and the transferring means separated from such loops. The loops of the final 25 knitted course of the article are thus brought together and may be connected by further knitting or stitching as desired.

30 The method is concerned with the bodily transfer of the article from the knitting machine with the loops of the final course each independently held; the arrangement of such loops in alined pairs to close the opening; and the transferring of such alined loops together onto a holding device by 35 which they are maintained in proper relative positions for final securing.

In the drawings:—

Figure 1 is a broken sectional view, illustrating the application of the transferring device to a circular knitting machine, the loops of the final course being shown in some instances in positions on the fingers of the transferring device.

Fig. 2 is a perspective view of the transferring device and ring carrier therefor.

Fig. 3 is a similar view of both sections of the transferring device removed from the carrier and in position to close the article opening by bringing the opposed loops together.

Fig. 4 is a detail view of a modified form of the invention.

In the drawings, the transferring device is made up of two identical sections, each comprising a resilient or flexible strip 1, to which are secured the transferring fingers. These fingers each include a rectangular block-end 2, from which the finger extends in a return bend at 3, and depends in a quill portion 4, in parallelism with and extending below the block-end 2. The quill portion 4 is grooved on the inner side, as at 5, to receive or coöperate with the needle 6 of the knitting machine, and is terminally reduced to a fine edge or point.

The strips 1 are each of such length that when bent into semi-circular form and arranged end to end they will provide a circular member corresponding to that of the needle plane of the knitting machine, as shown in Fig. 2. The fingers are secured to the strips 1 with their block ends in contact, the block ends being preferably slotted as at 7 to permit the securing of the same to the strips. Each section of the transferring device is thus made up of a series of fingers, corresponding in number to one-half the number of needles of the machine, with the block ends of such fingers in contact and supported on a resilient strip to permit arranging the fingers in circular form.

For application in the transferring operation, the respective sections of the transferring device are, when arranged in circular form, held in such form by a ring carrier 8, having an annular wall 9 against which the block-ends of the fingers bear to maintain the circular relation of the transferring sections. The lower edge of the carrier ring has an outstanding ledge 10 to support the transferring sections, movable latches 11 carried by the upper edge of the ring holding the sections in place.

With the transferring sections in circular form in the ring carrier, the device is applied to a knitting machine, each finger coöperating with a needle 8, and passing through the loop 12 of the final course of the knitted article. The said loops 12 are then moved upwardly by hand onto the quills 4, the needles 6 resting in the grooves 5 of the quills. The loops 12 are preferably carried onto the return bent portions 3 of the fingers. When all loops 12 have been so transferred, the device is removed with the ar-

ticle, and each loop 12 is on a separate finger of the transferring device.

If preferred after application of the transferring device through such loops 12, 5 the knitted article may be drawn upwardly, thus moving all loops 12 onto the transferring device at a single operation.

With the loops 12 on said fingers, the sections of the transferring device are removed 10 from the ring carrier, by opening the latches 11, and each transferring section, owing to the inherent resiliency of the strip 1 will straighten out into an elongated plane member, each carrying one-half the stitches 15 or loops of the final course of the fabric.

The transferring sections are then arranged in parallelism, with the quill portions of the respective fingers in contact. This alines opposed loops 12 of the article, 20 so that a pair of such loops are substantially together. A holder comprising a bar 13, having appropriately formed points 14 is then brought into use, each rod being passed through each pair of alined loops as shown. 25 The return bent portion 3 of each finger is preferably longitudinally recessed at 15 to permit the convenient passage of the ends of the points through the loops.

With the opposed loops in pairs on the 30 holder points, the fingers of the transferring sections are separated from the loops, by turning each section in succession and sliding the quill portion of the fingers from engagement with the loops, and the said loops 35 are left on the points, each rod engaging both opposed loops of the final knitted course of the fabric. The opening is thus closed, its edges being formed by the loops on the points, and in this position, such juxtaposed loops may be knitted together, 40 stitched or otherwise connected.

The fingers could be supported on hinged sections, as shown in Fig. 4, which will form a flexible structure and accomplish the result described in connection with the preferred form of the invention. In this figure, 45 20, indicates links, hinged together at 21, and supporting the fingers as at 23.

Claims:

50 1. The herein - described method of arranging the loops of the final course of a knitted article in a relation to be secured together to close the opening of such course, consisting in providing means for and transferring by such means the final loops in 55 circular outline from the knitting machine, arranging such loops while on said transferring means to position opposed loops of such final course adjacent to each other in 60 such pairs, and finally providing means for and removing by such means each pair of loops separately from the transferring means and

holding such pairs of loops in relation and position for final securing together.

2. A transferring device for knitted articles, comprising two normally straight sections, fingers carried by the sections to engage the needles and receive the loops, and a ring carrier in which said sections may be held to circular form.

3. A transferring device comprising two sections, each including a resilient normally straight strip, blocks arranged on each strip and held against other than a sliding movement thereon, a knitting needle engaging 75 finger secured to each block, said finger receiving the loops from the needles, and a ring carrier in which the blocks are positioned to hold the strips in circular form.

4. A transferring device comprising two sections, each including a straight strip, knitting needle engaging fingers secured to such strip, said fingers receiving the loops from the needles, and each finger having a 80 curved portion adjacent the strip and a quill projecting from such curved portion, and a ring carrier in which said strips may be held in circular form, the quill of each finger being grooved to receive the needle 85 of the knitting machine.

5. A transferring device for knitted articles, comprising two resilient sections, fingers carried by the sections to engage the needles and receive the loops, and a ring carrier in which said sections may be held 90 to circular form.

6. A transferring device for knitted articles comprising a plurality of fingers, means for supporting the fingers to permit of the same being arranged in circular form 100 or collapsed to bring one-half the number of fingers adjacent the remaining half of the fingers, and a ring carrier in which the fingers may be held to circular form.

7. A transferring device for knitted articles comprising a plurality of fingers, means for supporting the fingers in circular form to take off all the loops from the needles of a knitting machine, and to permit of the plurality of fingers being collapsed to 110 form straight parallel rows, the fingers in one row bearing against the fingers of the adjacent row, whereby to permit of the insertion of a plurality of points to remove all the gathered loops from the fingers.

In testimony whereof we affix our signatures.
